UNITED STATES PATENT OFFICE.

JOHN T. WARD, OF LOS ANGELES, CALIFORNIA.

DUST-CAP FOR TIRE-VALVES.

1,304,424.

Specification of Letters Patent. Patented May 20, 1919.

Application filed April 19, 1918. Serial No. 229,483

To all whom it may concern:

Be it known that I, JOHN T. WARD, a citizen of the United States, residing at Los Angeles, in the county of Los Angeles and State of California, have invented new and useful Improvements in Dust-Caps for Tire-Valves, of which the following is a specification.

Heretofore it has been the common practice to use a dust cap for tire valves which screws upon the valve stem. While this is very positive in its construction, yet it is objectionable because of the time required to remove and replace the cap. It has been proposed to use caps which are held in position by bayonet joints, but these rattle and become loose. Where locking arrangements for such caps has been employed, they have generally been exposed to dust so that they soon clog and become inoperative.

The primary object of this invention is to provide a cap which protects the valve from dust, may be quickly removed and replaced, and is securely locked in position when in place.

It is another object of this invention to provide a cap which is dust tight, and which is protected against clogging so that it will always be operative.

It is a still further object of this invention to provide a cap of the character described which contains the movable elements, and whereby in case of injury it will only be necessary to secure a new cap, it being practically impossible to injure the base portion of the cap surrounding the stem.

I accomplish these objects by means of the embodiments of my invention illustrated in the accompanying drawing, in which:

Figure 1 is a section through a valve equipped with my improved dust cap, the valve stem being partly shown in elevation. Fig. 2 is a section as seen on the line 2-2 of Fig. 1, the cap being removed. Fig. 3 is a section through the cap as seen on the line 3-3 of Fig. 1. Fig. 4 is an enlarged fragmentary section as seen on the line 4-4 of Fig. 2. Fig. 5 is an enlarged fragmentary section as seen on the line 5-5 of Fig. 2.

Referring more particularly to the drawing, 6 indicates the usual valve stem extending through the rim 7 of a wheel. The base of the dust cap is indicated generally by 8, and the cap proper is indicated generally by 9.

The base 8 has its lower portion of hexagonal form so as to provide a wrench hold. The upper portion is of cylindrical form as indicated by 10. The topmost portion may be squared as indicated by 11. Upon the square portion is disposed a collar 12, which may be riveted in place or secured by any other suitable means. However, the collar 12 may be made integral with the base 8. The construction is such that an annular channel 13 is formed in the base. The collar 12 has notches 14 formed therethrough. Midway between notches 14 are recesses 15.

The cap 9 is a shell having a portion 16 of such diameter that it telescopes over the portion 10 of the base and forms a dust tight fit. The upper portion 17 is preferably reduced in diameter so that a shoulder 18 is formed in the cap. On the inside of the cap spaced from the open end thereof are lugs 20 so disposed that, when the cap is slipped over the base portion of the cap, the lugs 20 may pass through the notches 14 and into the channel 13. Resting upon the lugs 20 is a ring 21, which has a bore 80 larger than the stem of the tire valve so that it is free to move thereover. Disposed between the ring 21 and shoulder 18 is a helical compression spring 22, which tends to force the ring 21 upon the lugs.

The cap is placed in position by slipping it over the cylindrical portion 10 of its base, then pressing downwardly and rotating the cap until lugs 20 register with notches 14. The cap is then forced downwardly until the lugs 20 are disposed in the channel 13. The spring 22 acting upon ring 21 resists this movement very slightly. When the lugs have reached their lowest position and rest upon the bottom of the channel, the cap is rotated a slight amount. The downward pressure upon the valve cap is relieved, and when the lugs 20 reach the recesses 15 they will slip upwardly therein and be locked in position. To remove the cap, it is only necessary to press downwardly upon the same, then rotate the cap until the lugs 22 register with the notches 14. In this position, the action of the spring 22 upon the ring 21 forces the lugs upwardly and out of the notches, thereby releasing the cap.

The portion of the valve cap overlapping its base forms a dust tight connection. It also serves to firmly hold the cap in position and prevents rattling. With this con-

struction it would be sufficient to have two lugs, although any greater number than two may be used. It will also be noticed that the ring 21 and the spring are contained 5 within the cap so that the cap proper is self contained. After removing the cap the same may be slipped into the pocket and there is no opportunity for mud or dirt to get into the parts and clog them so as to 10 prevent operation of the cap. This is a very important feature of my invention.

What I claim is:

The combination of a base portion of a tire valve dust cap having a cylindrical 15 upper end, a peripheral channel being formed therein adjacent the upper face, the

upper wall of said channel having notches extending therethrough and recesses between said notches, a cap for said stem having a bore with lugs extending inwardly and disposed to pass through said notches and rest within said recesses, said lugs being spaced above the lower edge of the cap so that the latter will telescope over the cylindrical part of said base portion, a ring slidably 20 disposed within said bore, and a compression spring resting against said ring tending to hold said ring upon said lugs.

In witness that I claim the foregoing I have hereunto subscribed my name this 12th 25 day of April, 1918.

JOHN T. WARD.
